UNITED STATES PATENT OFFICE.

LOUIS JOHN JAEGER, OF COLUMBUS, NEBRASKA.

MILK-BOTTLE SAFE.

Application filed February 10, 1923. Serial No. 618,373.

To all whom it may concern:

Be it known that I, LOUIS JOHN JAEGER, a citizen of the United States, and a resident of Columbus, in the county of Platte 5 and State of Nebraska, have invented certain new and useful Improvements in Milk-Bottle Safes, of which the following is a specification.

My invention relates to improvements in 10 milk bottle containers, and it consists of the constructions, combinations and mode of operation herein described and claimed.

An object of the invention is to provide 15 a milk bottle container in the nature of a safe which embodies provisions not only insuring against the theft of full milk bottles but also makes it necessary to set out an empty bottle before the full bottle may be taken from the container.

20 A further object of the invention is to provide a milk bottle safe which primarily has two compartments and locking means which so control the doors of the compartments that it becomes necessary for the 25 housewife to place an empty bottle in one of the compartments before the full bottle may be taken from the other compartment, and on the other hand, makes it necessary for the milkman to place a full bottle in the 30 last named compartment before he can open the door to the other compartment and take the aforesaid empty bottle.

Other objects and advantages will appear 35 in the following specification, reference being had to the accompanying drawings, in which:

Fig. 1 is a perspective view illustrating the general aspect of the improved milk bottle safe,

40 Fig. 2 is a cross section taken substantially on the line 2—2 of Fig. 1,

Fig. 3 is an inverted plan view of the safe, the observer assuming a position opposite to that which must be assumed to obtain the 45 view in Fig. 1,

Fig. 4 is a cross section taken on the line 4—4 of Fig. 3, and

50 Fig. 5 is a detail sectional perspective view showing the lock mechanism in detail, the milk bottle safe being viewed from a position corresponding to that in Fig. 1.

In carrying out the invention, provision is made of a cabinet 1 which has a top 2 and floor 3 (Figs. 2, 4 and 5). The back 4 and front 5 extend down from the top 2 until 55 they meet a flange 6. The sides 7, however, extend down from the floor 3 only (Figs. 2 and 4), this arrangement defining a space in which the milk bottles are to be placed.

A partition 8 divides this space into two 60 compartments 9 and 10 (Figs. 4 and 5) which are repeatedly referred to below as the empty and full milk bottle compartments, respectively. The ends of the compartments 9 and 10 are adapted to be closed 65 by doors 11, 12 and 13, 14.

These doors work in pairs, that is to say, they are adapted either to be locked together or adapted to be opened together. This may be illustrated by an example in 70 advance of the description of the mechanism, the understanding of which will make this feature clearer. Unless the housewife puts an empty bottle into the compartment 9, the pair of doors 13 and 14 will remain 75 locked so that access to the compartment 10 cannot be had.

Placing an empty bottle into the compartment 9 will unlock the doors 13 and 14 so that either one or the other, or both, may 80 be opened to gain access to the compartment 10. Upon placing a milk bottle in the compartment 9, and permitting both doors 11 and 12 to close, a locking of these doors will be effected. The milkman cannot open either door 11 or 12 unless he places a full bottle in the compartment 10. He can then open either one or the other of doors 11 and 12 to get the empty milk bottle. The doors 13 and 14 will not become locked unless he 85 takes the empty milk bottle out. Upon taking the empty milk bottle out, both doors 13 and 14 become locked until the housewife again places an empty milk bottle in the compartment 9, whereupon both doors 13 and 14 90 become unlocked so that the full bottle can be taken out.

This advance description makes it plain to the reader that the two pairs of doors operate together, and this being so, it is 100 equally clear that there is merely a duplicate arrangement of the doors so that access

to the cabinet may be had from one side or the other. A flange 15 extending up from the back 4, provides a convenient means for fastening the cabinet to any suitable support. The flange 6, referred to above, extends completely around the cabinet.

A bottom 16 is slid in place on opposite flanges, for instance, those on the back 4 and front 5. The corresponding edges of the bottom are curled over so as to form guides admitting these flanges. The bottom has a ring 17 by which the bottom can be moved in place or removed when desired. The bottom also includes a lug 18 adapted to register with a corresponding lug 19 on the side 7 nearest to the observer in Fig. 1, so that a lock 20 may be applied to keep the bottom 16 in place and prevent meddling with the locking mechanism. This mechanism is situated in a lock chamber 21 (Figs. 2, 3 and 4) which is defined by the floor 3, bottom 16 and the various sides of the cabinet 1.

The various doors are hinged at 22 on the back and front walls 4 and 5, and for the purpose of opening the doors, each is provided with a knob 23. The locking means includes springs by which the doors are closed. These are specifically referred to in the description of the locking mechanism below, but in addition to these springs, other springs 24 (Fig. 2) are employed in connection with each door to assist in closing. These springs are located at the top so as to equalize the closing effort.

Sets of indicators 25 and 26 are situated on the front wall 5. These indicators are in the nature of metallic flags which in practice have legends designating various quantities of milk or cream desired. All of this is readily understood from Fig. 1. Since the various flags are mounted on a common pivot, any desired one may be moved to the erect position.

Consider now the locking mechanism. A platform 27 in the compartment 9 is pivotally mounted at one side on a rod 28. The rod 28 is supported in the opposite portions of a flange 29 which depend from the floor 3 and bounds the opening 30 (Fig. 5) in which the platform 27 operates.

The weight of a milk bottle (empty in this case) on the platform 27 in the compartment 9, causes the weight lock rod 31 to rock so that the bolts 32 and 33 are withdrawn from the keepers 34 and 35 of the doors 13 and 14 which close the compartment 10. This rocking of the rod 31 is accomplished by a crank 36. A spring 37, which has connection with a crank 38 in the lock rod, keeps the crank 36 in contact with the platform 27 and tends to move the bolts 32 and 33 upward.

Connected to the doors 11 and 12 at 39 and 40, (Figs. 3 and 5) are springs 41 which

converge to a common point of connection at a crank 42 of a door-operated lock rod 43. This lock rod terminates in bolts 44 and 45 which (with the bolts 32 and 33) are also adapted to enter the keepers 34 and 35 of the doors 13 and 14.

The closure of the doors 11 and 12 permits a spring 46 to rock the door-operated lock rod 43 through the medium of the crank 42 in such a direction as to retract the bolts 44 and 45 from the keepers 34 and 35. Should either the door 11 or 12 be in the open position, the crank 42 would be moved in the opposite direction through the medium of one or the other of the springs 41 and thereby move both bolts 44 and 45 into engagement with said keepers. In order to permit opening either door 13 or 14, it is necessary for the housewife to set a milk bottle upon the platform 27 in the compartment 9, thereby causing the weight lock rod 31 and the bolts 32 and 33 to rock downward and release said doors 13 and 14 for opening.

However, before this can be done, the doors 11 and 12 must be closed upon the milk bottle now in the compartment 9 in order that the bolts 44 and 45 also may be retracted from engagement with the keepers 34 and 35. A similar lock arrangement obtains in respect to the compartment 10. A platform 47, situated in this compartment, is pivotally mounted at one side on a rod 48. This rod is supported on opposite side members of a flange 49 which is bent downwardly from an opening 50 in the floor 3. A spring 51 (corresponding to the spring 37) has connection with a crank 52 in a weight lock rod 53, this spring keeping a crank 54 in contact with the platform 47 and also tending to keep bolts 55 and 56 in engagement with keepers 57 and 58 on the doors 11 and 12.

Connected at 59 and 60 (Figs. 3 and 5) to the doors 13 and 14, are springs 61 which converge to a common point of connection at the crank 62 of a door-operated lock rod 63 on the opposite side of the cabinet. In this connection it is to be noted that the doors (13 and 14 for example) of one compartment, are adapted to actuate the door-operated lock rod which is situated under the other compartment, and which is adapted to lock the doors of said other compartment. On the same principle, the platform (47 for example) of one compartment is adapted to actuate the weight lock rod (53 for example) which controls the locking bolt of the doors of the other compartment.

Referring again to the door-operated lock rod 63, this, at the extremities, has bolts 64 and 65 which also are adapted to engage the keepers 57 and 58 of the doors 11 and 12. The opening of either door 13 or 14 will cause a pull on either spring

61 so that the bolts 64 and 65 are made to engage the aforesaid keepers. This act is contrary to the tension of a spring 66 which also has connection with the crank 62. The closing of either door 13 and 14 permits the spring 66 to retract the bolts 64 and 65 from the aforesaid keepers so that the doors 11 and 12 are free to open in so far as the locking function of the doors 13 and 14 is concerned. It is necessary to set a milk bottle (full in this instance) on the platform 47 before the bolts 55 and 56 will be retracted from the keepers 57 and 58 and thereby permit the opening of the doors 11 and 12.

Movement of the various lock bolts is limited by suitable stops. The door-operated bolts 64 and 65 move between lugs 67 and 68 (Fig. 3). The movement of the weight lock bolts 32, 33 and 55, 56 is limited by lugs 69. The door-operated lock bolts 44 and 45 move between lugs 70 and 71. All of the various lugs project into the lock chamber 21 from the side walls 7.

The side walls 7 also have slots 72 (Fig. 5) through which the various converging springs 41 and 61 pass when the respective doors to which they are attached are opened. Provision is made of bearings 73 and 74 for the support of the various lock rods 31, 63 and 43, 53 (Fig. 3). These bearings may consist of depending sheet metal brackets fastened underneath of the floor 3, and at the places where these rods pass the peripheral flanges 29 and 49 at the platforms 27 and 47, adjacent portions of these flanges are merely made deeper to constitute brackets in which the rods have supports. This is illustrated in the instance of the bearing 74 in Fig. 4. This view also shows the use of a yoke 75 which is carried by the platforms and embraces the adjacent weight lock rods 31 and 53 to limit the lifting movement of each platform on the associated pivot rod.

The operation may be reviewed in connection with the foregoing description and thereby possibly bring out features which are not made entirely clear. The compartment 9 is for empty milk bottles and the compartment 10 is for full milk bottles. The tilttable platforms 27 and 47 in these respective compartments may, with very little modification, be made to extend the full length of the respective compartments instead of occupying approximately only one-half the length. This modification would have the advantage of insuring the tilting of the platform upon putting a milk bottle into the safe.

Assume that the housewife places an empty bottle into the compartment 9. In doing this, care must be taken to set the bottle upon the platform 27. The housewife cannot help but do this, especially when two empty quart milk bottles are put

into the compartment 9. The doors 11 and 12 are now closed. That is to say, one or the other of doors 11 and 12 is permitted to close because it is improbable that the housewife would open both doors in order to set an empty milk bottle into the compartment 9.

The springs 41 (Figs. 3, 4 and 5) and 24 (Fig. 2) cause the closing of the aforesaid doors. As soon as these doors are closed they become locked. This is due to the fact that the locking bolts 55 and 56 occupy an extended or erected position as long as there is no weight on the platform 47 in the other compartment 10. The keepers 57 and 58 are fixed in an inclined position upon the respective doors so that as the doors close, the inclined keepers perform a wedge action on the adjacent ends of the bolts 55 and 56, depressing them so that the keeper may pass into position over the bolts. The principle is the same as that of an ordinary spring latch.

Assume next that the milkman comes along. He may attempt to open either door 11 or 12 to take the empty milk bottles, but is prevented from doing this because of the fact that they are locked, as just explained. However, he may open either door 13 or 14 because it is intended that he should do so in order to put the full bottle of milk into the compartment 10. Neither door 13 nor 14 is locked when there is an empty bottle in the compartment 9 and when both doors 11 and 12 are closed. The weight of the bottle on the platform 27 rocks the weight lock rod 31 by virtue of the crank 36 so that the bolts 32 and 33 are retracted from the keepers 34 and 35 of the doors 13 and 14. The closing of the doors 11 and 12 permits the spring 46 to pull back on the crank 42 and retract the door-operated lock bolts 44 and 45 from the keepers 34 and 35.

Now having access to the compartment 10, the milkman places a full bottle on the platform 47. This rocks the weight lock rod 53 by virtue of the crank 54 so that the bolts 55 and 56 are retracted from the keepers 57 and 58. Although this one locking means is thus rendered inoperative, the doors 11 and 12 are, nevertheless, still locked. This is so because it is assumed that the milkman is still holding one or the other of the doors 13 and 14 open. This act causes a pull on one or the other of the springs 61, a forward rocking of the crank 62 on the door-operated lock rod 63 so that the bolts 64 and 65 are moved up into the keepers 57 and 58 in place of the bolts 55 and 56, as aforesaid.

In order that the milkman be permitted to get the empty milk bottle from the compartment 9, he must close both doors 13 and 14. This relaxes the spring 61, permits the spring 66 to pull the lock rod 63 back and thus re-

tracts the bolts 64 and 65. There is now a full milk bottle on the platform 47 and the bolts 55 and 56 stand retracted. Either door 11 or 12 may now be opened and the milk bottle taken out. The removal of the weight from the platform 27 permits the locking bolts 32 and 33 to spring up into engagement with the keepers 34 and 35 so that the full bottle of milk in the compartment 10 is safe from anyone who might wish to take it.

Even the housewife cannot get the full bottle of milk unless she opens one or the other of the doors 11 and 12 and places another empty milk bottle on the platform 27. She is next compelled to close the doors to the compartment 9 so as to retract the bolts 44 and 45 from the respective keepers, the bolts 32 and 33 having been retracted by 20 the act of placing the bottle on the platform 27. Either door 13 or 14 can now be opened to take the full milk bottle, but the doors 11 and 12 are again locked by the attendant release of weight from the platform 47 so that the empty milk bottle cannot be re-taken from the compartment 9.

One of the advantages of this milk safe is that the housewife will always have her milk bottle out, that is to say, the full milk 30 bottle cannot be obtained unless an empty bottle is placed into the safe for the next day's supply. Another advantage of the milk safe is that the stealing of both full and empty milk bottles is safeguarded 35 against. Furthermore, stray animals are prevented from getting at the milk bottles, this often being the case when milk bottles are left exposed on door steps, etc.

While the construction and arrangement 40 of the improved milk bottle safe as herein described and claimed is that of a generally preferred form, obviously modifications and changes may be made without departing from the spirit of the invention or the scope 45 of the claims.

I claim:

1. A milk bottle safe comprising a cabinet having empty and full bottle compartments, a door for each compartment, a keeper on the full bottle compartment door, a weight lock rod having a bolt adapted to engage said keeper and lock the door, a tiltable platform in the empty bottle compartment adapted to rock the lock rod and retract the bolt from said keeper upon imposing the weight of an empty bottle upon said platform, a door operated lock rod having a bolt normally disengaged from said keeper, and means in connection with the empty 55 bottle compartment door adapted to rock said door-operated lock rod and move said bolt into engagement with the keeper upon opening said empty bottle compartment door.
- 60 65 2. A milk bottle safe comprising a cabinet

having empty and full bottle compartments, a door for the full bottle compartment, a keeper on said door, a lock rod disposed under the empty bottle compartment and having a bolt normally engaging said keeper, means by which the lock rod is rocked to keep the bolt in said position, a platform in the empty bottle compartment, means upon which it is pivoted, and a crank in said lock rod kept in contact with the platform and being adapted to move the bolt from engagement with the keeper upon setting an empty bottle on said platform.

3. A milk bottle safe comprising a cabinet having empty and full bottle compartments, a door closing the full bottle compartment, a keeper on said door, a lock rod under the full bottle compartment having a bolt, a spring normally keeping the bolt from engagement with the keeper, a door for the empty bottle compartment, and connecting means between the empty bottle compartment door and said lock rod adapted to move the bolt into engagement with the keeper against the tension of said spring upon opening of said door to lock the full bottle compartment door.

4. A milk bottle safe comprising a cabinet having empty and full bottle compartments, a pair of doors for the full bottle compartment, a keeper on each door, a lock rod disposed under the empty bottle compartment having bolts normally engaging said keepers, means including a spring by which the lock rod is rocked to keep the bolts in said position, a platform in the empty bottle compartment, means upon which it is pivoted, and a crank in said lock rod kept in contact with the platform by said spring and being adapted to move the bolts from engagement with the keepers upon setting an empty bottle on said platform.

5. A milk bottle safe comprising a cabinet having empty and full bottle compartments, a pair of doors closing the full bottle compartment, a keeper on each door, a lock rod under the full bottle compartment having bolts and a crank, a spring in connection with the crank normally keeping the bolts from engagement with the keepers, doors for the empty bottle compartment, and connecting means between each of the empty bottle compartment doors, and the crank of said lock rod adapted to move the bolts into engagement with the keepers against the tension of said spring upon opening either of the doors of the empty bottle compartment to thereby lock the full bottle compartment doors.

6. An exchange receptacle comprising a pair of compartments, a door for each compartment, a keeper on the door, a pair of lock rods under each compartment, a bolt carried by each of the lock rods, the bolts of the respective pairs being adapted to en-

gage the keepers of the local and opposite doors respectively, cranks in the lock rods which control the opposite doors, platforms with which said cranks engage and by which the associated doors may be moved out of engagement with the keepers of the opposite doors, means keeping the remaining lock rods and bolts out of engagement with the local keepers, and means connecting said lock rods with the opposite doors to move 10 said bolts into engagement with said keepers when said opposite doors are opened.

LOUIS JOHN JAEGER.
